CONCRETE FENCE

Louis A. Goossens, Centerline, Mich.

Application May 23, 1955, Serial No. 36,164

Term of patent 14 years

(Cl. D28—2)

Fig. 1 is a plan view of a concrete fence embodying my new design;

Fig. 2 is an elevational view of the concrete fence as seen in Fig. 1; and

Fig. 3 is a cross-sectional view of the concrete fence taken on the line 3—3 of Fig. 2.

The dotted lines of the drawing indicate indeterminate length.

I claim:
The ornamental design for a concrete fence, as shown.
